UNITED STATES PATENT OFFICE

WILLIAM L. HANCOCK, OF DALLAS, TEXAS, ASSIGNOR TO THE MURRAY COMPANY, OF DALLAS, TEXAS, A CORPORATION OF TEXAS

COTTON CLEANER

Application filed August 9, 1929. Serial No. 384,605.

This invention relates to new and useful improvements in cotton cleaners.

One object of the invention is to provide a structure wherein the beater bearing boxes are hung from the underside of the frame, together with a hinged bottom casing section; whereby the bearing boxes may be more readily replaced and access had to the beaters and their journals for purposes such as adjusting, repairing, cleaning and the like.

A further object of the invention is to provide a hinged front for the casing for giving access and co-acting with the hinged bottom to permit cleaning of the screens.

Another object of the invention is to provide a cleaner suspended at its upper side, thus permitting its bottom to be free from supports and easily removed.

Still another object of the invention is to provide means for opening the boll breaker for cleaning the same and to give access to the parts thereof.

A construction designed to carry out the invention will be hereinafter described together with other features of the invention.

The invention will be more readily understood from a reading of the following specification and by reference to the accompanying drawings in which an example of the invention is shown, and wherein:

Figure 1 is a front elevation of the cleaner,

Figure 2 is a side elevation of the cleaner,

Figure 3 is a vertical sectional view of the cleaner with the side cover removed,

Figure 4 is a vertical sectional view showing the screw conveyor,

Figure 5 is a view showing a section of a drum with its spaced radial pins or spikes mounted thereon,

Figure 6 is a sectional end view of the same,

Figure 7 is a sectional view of the boll breaking roller and breaker bar;

Figure 8 is an end view of the same,

Figure 9 is a view showing a section of the feed roller,

Figure 10 is an end view of the same,

Figure 11 is a view showing a section of the guide bar and teeth,

Figure 12 is an end view of the same,

Figure 13 is a plan view of the same, and

Figure 14 is a detail of the concave screens.

In the drawings the numeral 10 designates an inclined channel iron frame hung from a beam 11 by bolts 12, which beam is supported upon front legs 14 and rear legs 13. A bottom casing is mounted upon parallel wood supports 50 which are disposed transversely at each side of the casing as a whole. The wood supports are swung from a rod 17 which is journaled in a lower frame 18. Angle iron braces 16 are mounted upon the casing 15. The bottom casing 15, when released by latches 19 and the braces 16 are unbolted from the lower frame 18, will swing open to the position shown in dotted lines 65 in Figure 2, thus allowing replacements and oiling of drums and parts.

The casing as a whole is disposed at a downward angle to the perpendicular, whereby its bottom is inclined downwardly 70 to a discharge hopper 20 which has a screw conveyor 21 journaled in the lower frame 18, to which is attached a drive pulley 22. On top at the lower end of the casing is a boll breaker hopper 23 which consists of a pair 75 of feed rollers 24 mounted on shafts 61 and 62, which turn inward as indicated by arrows and present the cotton in a compressed bat to a boll breaking roller 25 mounted on a shaft 60, having projecting spikes or teeth 80 26.

At one side of the breaker roller 25 is pivoted a breaker bar 27 having teeth 28 so arranged as to pass between the teeth 26 of the roller 25. This bar is held to the roller by 85 coiled springs 35, whereby the bar will yield downwardly and permit hard foreign articles, such as rocks and metal, to pass without injury to the boll breakers. A breaker bar 27 is mounted on a shaft 29 which is journaled in suitable bearings in the casing 23.

Attached on the shaft 29 is a lever 30 actuated by a rod 31 which is secured to a control handle 32 mounted on the leg 14. The control handle regulates the space between the breaker bar 27 and the roller 25. A guide bar 33 having teeth 34 so arranged as to pass between the teeth 28 of the breaker bar 27, is situated immediately below the breaker 100 95

bar 27 and is mounted on a brace 36 of a frame 37.

A screen 38 made of sheet metal and punched with staggered perforations 39 is mounted on the frame 37 which also carries a bottom end casing 40. The frame 39 is swung from a rod 41 in such a manner that it can be raised to the position shown in dotted lines in Figure 2, thereby allowing replacements, oiling, and cleaning of working parts. A front casing 42 of a protruding portion 43 of the hopper 23 can be swung open by means of hinges 44, to the position shown in dotted lines in Figure 2, thereby allowing for replacements, cleaning and oiling of parts.

A series of drums 45 studded with longitudinal rows of radial pins or spikes 46 are mounted on shafts 47 which are journaled in bearings 48. Bearings 48 are spaced evenly and mounted on the underside of the channel iron frame 10. The perforated screen 38 is disposed transversely of the casing 15 and is supported by cross rails 49 which are secured to wood supports 50 of the casing 15. The screen is shaped concavely between the cross rails 49 in such a manner that the spikes of a drum will drag the cotton over the concave section of the screen and pass it onto the next concave section until it reaches a discharge spout 51, which is located at the top end of the bottom casing 15.

In the bottom of the hopper 20 is an outlet 52 to which a suction trunk 53 is attached by means of a latch 54. This suction trunk 53 is connected to an air blower 55 which discharges the dirt and trash, that has been removed from the cotton, to any convenient location. On a drive shaft 56 of the air blower 55 is mounted a pulley 57 with a pulley belt 58 which is mounted at the other end to a pulley 59 attached to a shaft 60 on which the boll breaker roller 25 is mounted.

A pulley 63 mounted on a shaft 61 has a drive belt 64 which is mounted at the other end on a pulley 65 attached to the most convenient drum shaft 47. The shaft 62 is driven by an attached gear 68 which is meshed with a pinion (not shown) that is mounted on the shaft 61. The shafts 47 are driven by a combination of belts 66 mounted on pulleys which are attached to the shafts. Deflectors 67 attached to casing braces 68 prevent the cotton from being thrown backward by the drums.

The operation is as follows:

The seed cotton with its accompanying foreign matter is received in the hopper 23 and is acted upon first by the feed rollers 24 turning inward, as indicated by arrows, which engage and compress the seed cotton into a bat and presents it to the teeth of the rapidly rotating boll breaker roller 25. The roller 25 co-acting with the breaker bar 26 hammers the bat and bolls, thus breaking without crushing. Any hard material likely to injure the teeth will swing the bar 27 down-

wardly and thus pass through without harming these parts. The cotton after passing the roller 25 slides down the screen 38 and is engaged by the first of the series of drums 45.

The cotton is then carried forward and upward by the drums 45 over the screens 38 and passed out through the discharge spout 51. The deflectors prevent the cotton being thrown backward by the drums. The foreign matter remaining in the cotton after it passes the roller 25 is extracted during the passage over the screens.

The dirt and trash after passing through the perforations 39 of the screens 38 will collect in the hopper 20 and will then be carried to the outlet 52, by the screw conveyor 21, from where it will be carried through the trunk 53 by air suction to a convenient dump.

Various changes in the size and shape of the different parts, as well as modifications and alterations, may be made within the scope of the appended claims.

What I claim, is:

1. In a cotton cleaner, a front support, an upright supporting frame, inclined supports attached to the front support at their lower ends and extending through the upper portion of the supporting frame, elements depending from the top of the frame and attached to the inclined supports for suspending the latter, the inclined supports extending beyond the frame, cleaning drums journaled on the inclined supports, and a bottom screen member contiguous to the drums and hinged at the upper ends of the inclined supports so as to swing free of and in rear of the upright frame when opened.

2. In a cotton cleaner, an elevated inclined casing, a bottom hinged to the inclined casing and mounted to swing to a vertical position when released, a front closure for the casing mounted for pivotal movement, and a cleaning screen in the casing located to be entirely exposed from end to end when the bottom and the front closure are swung to their open positions.

3. In a cotton cleaner, an inclined casing, a front support for the lower end of the casing, a suspending frame for the casing considerably wider than said casing, means for suspending the casing within the frame, whereby substantial clearance spaces are provided between the frame and the casing on each side, journal boxes mounted in the casing, cleaner drums carried by the boxes, and a hinged bottom arranged to be swung downwardly and away from the boxes and drums, whereby said drums may be lowered or raised from the casing and within the frame.

In testimony whereof I affix my signature.

WILLIAM L. HANCOCK.
